UNITED STATES PATENT OFFICE.

AUBREY AUGUSTUS EDEY, OF MOBILE, ALABAMA.

SPARK-PLUG.

1,167,804.

Specification of Letters Patent. Patented Jan. 11, 1916.

Application filed October 1, 1915. Serial No. 53,560.

To all whom it may concern:

Be it known that I, AUBREY A. EDEY, a citizen of the United States, residing at Mobile, in the county of Mobile and State of Alabama, have invented certain new and useful Improvements in Spark-Plugs; and I hereby declare that the following is a full, clear, and exact description thereof, reference being had to the accompanying drawings, which form part of this specification.

This invention relates to ignition or spark plugs employed in connection with gas or other types of explosive engines.

In spark plugs as ordinarily constructed, the end is open and the oil used to lubricate the piston is constantly being thrown up against and into the opening in or at the end of the plug, with the result that the spark points and the inside of the plug quickly become fouled with dirty oil and carbon.

The primary object of my invention is to provide a spark plug of the character referred to which will effectually exclude or prevent the oil used to lubricate the piston from being thrown up against and into the opening at the end of the plug, and thus prevent fouling the spark points and the inside of the plug.

A further object is to provide a removable cap or cover for the end of the plug that may be easily detached to permit any accumulation of lubricant or carbon that may occur to be readily cleaned off, so that the spark points and inside of the plug may be kept clean.

The invention will first be hereinafter more particularly described, with reference to the accompanying drawings, which are to be taken as a part of this specification, and then pointed out in the claims at the end of the description.

In said drawings, Figure 1 represents a side elevation of a spark plug embodying my improvement; Fig. 2 is a detail sectional view of the same; Fig. 3 is a perspective view of a removable cap or cover adapted to be screwed upon the end of the spark plug so as to form in effect an extension thereof open at its end with a baffle plate or cover for said open end; and Fig. 4 is a detail sectional view of a modification of the invention.

In said drawings, I have shown by way of illustration a spark plug having the usual insulating core A, of porcelain or other non-conducting material, inclosed or

embraced by a metal casting or casing B, which is exteriorly threaded to adapt it to be screwed into a suitably threaded opening in the cylinder of the engine; said parts being provided with the usual circuit terminals or spark points, such as commonly employed in this class of devices, so that further description thereof is deemed unnecessary.

C denotes a cap or cover which is detachably secured on the end of the tube or casting B and adapted to effectually cover the open end of the tube so as to prevent oil or other matter which may be splashed up from the underside of the cap from entering the hole in the end of the plug, and at the same time permit the admission of gas to and the escape of the waste products of combustion from the chamber in which the circuit terminals or spark points are located. To this end the cap C consists essentially of a cylindrical portion c, which is interiorly threaded to adapt it to be screwed upon an exteriorly threaded end or reduced extension b of the casing B; said cylindrical part c terminating in a conical portion c¹, which forms in effect, when the cap is screwed upon the casing B, a conical extension of the plug or tube B, open at its lower end. In close proximity to but slightly separated from said open end is a baffle plate or cover c², which is preferably connected with said cylindrical part c by means of two or more posts c³ integral therewith, so that the plate or cover c² will effectually cover the open end of the plug and prevent the entrance of dirty oil or carbon therethrough, so as to keep the oil away from the inside of the plug and away from the spark points, and thus insure a good spark at all times for firing the charge.

In Fig. 4 of the drawings I have shown a modification in which, instead of a plurality of posts, connecting the baffle-plate and cylindrical part of the cap, as shown in Figs. 1 to 3, the cap D is constructed with an inverted conical portion d and baffle plate d¹ integral with the conical portion of the cap and in effect forming an extension of the plug; said inverted conical portion being provided with a series of openings d² through the inclined wall of the part d, so as in effect to provide a series of standards connecting the baffle-plate and cap.

I thus provide a very effectual cover for the open end of the plug, which will pro-

tect the firing points located at said end, and prevent the entrance of dirty oil or carbon, as the result of an explosion and any accumulation of foul matter that may occur can 5 be easily and quickly removed by simply removing the cap and scraping with a knife or the like.

My improvement may be applied to any 10 of the common forms of spark plugs by providing on the end of the plug, below the usual threads for screwing it into the engine cylinder, a threaded portion or equivalent means for screwing on or securing the cap, as shown in Figs. 2 and 4 of the drawings. 15 A gasket or packing ring E of copper or other metal may be used to form an oil-tight joint between the plug proper and the attachment or cap.

It will be observed that the attachment or 20 cap of the described construction in effect serves to reduce the end of the plug and cover the hole therein, the cover being imperforate and so placed with reference to the opening in the end of the plug that the 25 total outlet around said edges of the opening, between it and the cover, is not less than the size of the reduced hole at the end of the plug. The cap is preferably made of brass, in one integral structure, by molding 30 or otherwise, though any suitable metal may be employed, and by its use the fouling of the sparking points is rendered practically impossible, as nothing can pass through the imperforate baffle-plate, and it also affords 35 a means for keeping the sparking points dry.

Having thus described my invention, what I claim as new and desire to secure by Letters Patent is:

1. In combination with a spark plug, an 40 open-ended cover for the electrodes of said plug carrying an imperforate baffle-plate in front of said opening and slightly separated therefrom.

2. In combination with a spark plug, a 45 cap for the spark points carried by said plug, said cap having a conical portion open at its apex and carrying a baffle plate slightly separated from said opening.

3. In combination with a spark plug having an open end, a cap secured on said end 50 having a conical portion open at its apex and in effect forming an extension of the

tube; said cap supporting a baffle-plate slightly separated from the opening in the apex of the cone.

4. In combination with a spark plug having an open end, a cap of cylindrical form screwed on said end and having a conical portion open at its apex and in effect forming an extension of the tube; said cap supporting a baffle-plate slightly separated from the opening in the apex of the cone; there being an uninclosed space between the apex of the cone and said baffle-plate.

5. In combination with a spark plug having an exteriorly threaded end, a cap of cylindrical form screwed on said end having a conical portion open at its apex and in effect forming an extension of the tube, and a baffle-plate carried by said cap slightly below and separated from the opening in the apex of the cone so as to leave an uninclosed space between said opening and said baffle-plate.

6. An attachment for a spark plug consisting of a substantially cylindrical body 75 interiorly threaded at one end to adapt it to be screwed on an exteriorly threaded end of the plug and carrying at its other end an imperforate plate supported by arms or 80 posts integral with said body and plate; said cylindrical body having a conical portion extending therefrom toward said plate and terminating close to the latter but slightly separated therefrom so as to leave an uninclosed space between the plate and the apex 85 of the cone, the latter having an opening in its apex.

7. In combination with a spark plug, a cap adapted to be secured to one end thereof 90 to cover the electrodes carried by said plug, said cap having a conical portion open at its apex, and means carried by said cap slightly in advance of said opening adapted 95 to prevent oil and dirt from splashing onto the electrodes of the plug.

In testimony that I claim the foregoing as my own, I affix my signature in presence of two witnesses.

AUBREY AUGUSTUS EDEY.
